UNITED STATES PATENT OFFICE

142,984

DESIGN FOR A DISPLAY FRAME

John W. Brown, Los Angeles, Calif.

Application April 2, 1945, Serial No. 118,826

Term of patent 3½ years

(Cl. D29—20)

To all whom it may concern:

Be it known that I, John W. Brown, a citizen of the United States, residing at 1881 Greenfield Avenue, Los Angeles, in the county of Los Angeles and State of California, have invented a new, original, and ornamental Design for Display Frames, of which the following is a specification, reference being had to the accompanying drawing, forming part thereof:

Fig. 1 is a front elevation of a display frame, showing my new design;

Fig. 2 is a side elevation thereof; and

Fig. 3 is a top plan view.

I claim:

The ornamental design for a display frame, as shown.

JOHN W. BROWN.
